ATTORNEY

UNITED STATES PATENT OFFICE

EDWARD McKNIGHT, OF AMSTERDAM, NEW YORK

FABRIC TAKE-UP FOR LOOMS

Application filed October 14, 1929. Serial No. 399,603.

This invention relates to a fabric controller for looms, the general object of the invention being to provide means for controlling the movement of the fabric to as many beats of the lay as is desired.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:

Figure 1 is a section on line 1—1 of Figure 2.

Figure 2 is a side view of Figure 1.

Figure 3 is a section on line 3—3 of Figure 1.

In these views, the numeral 5 indicates a part of the frame of the loom, 6 the shaft of the take-up roll thereof and 7 the ratchet which is connected with an end of said shaft. In carrying out my invention, I place a second idle ratchet wheel 8 on the end of the shaft adjacent the wheel 7, this wheel 8 being of larger diameter than the wheel 7 and having the shallow teeth 9 and the deep teeth 10 in its periphery. The power pawl 11 is of such width as to engage the teeth of both wheels, but when a small tooth 9 is under the pawl, said pawl is prevented from engaging the teeth of the power ratchet 7. When a large tooth 10 is under the pawl, the pawl will engage a tooth of the power ratchet so that both ratchets will be moved by the pawl. However, when the pawl is in engagement with a small tooth 9, only the idle ratchet 8 will be moved. The power pawl is attached to one limb of the member 12 which is rotatably mounted on the shaft and this member is connected in the usual manner with its operating means by the link 13. A holding pawl 14 is provided for each ratchet wheel, these pawls being arranged on a stub shaft 15. Thus it will be seen that the idle wheel moves with every beat of the lay of

the loom, but the power wheel only moves on every other beat, but it will be understood that by providing a different arrangement of teeth in the idle wheel, the power wheel can be made to move on as many beats of the lay, 55

From the foregoing it will be seen that I have provided simple means for controlling the movement of the fabric, so that the fabric is moved after the woofs have been laid and the bind has taken place so that nothing has been disturbed and a stronger and smoother piece of fabric is produced and one which has a more attractive appearance than fabric woven in the old way. 60

It is thought from the foregoing description that the advantages and novel features of the invention will be readily apparent.

It is to be understood that changes may be made in the construction and in the combination and arrangement of the several parts, provided that such changes fall within the scope of the appended claim. 70

What I claim is:

A fabric take-up for looms including a loom frame carrying a roll shaft and a power ratchet wheel therefor and having teeth engaged by a power pawl, an extension on the hub of the ratchet wheel, an idle ratchet wheel journaled on the extension and of a diameter larger than the diameter of the power ratchet wheel, deep and shallow teeth on the idle ratchet wheel with the pawl in engagement therewith and the deep teeth thereof being of the same depth as the depth of the teeth of the pawl ratchet wheel to permit said pawl to rotate said power ratchet wheel during certain movements thereof and to be disengaged therefrom by engaging the shallow teeth for imparting an intermittent movement to the roll shaft, and pawls pivoted to the frame and engaging the ratchet wheels to prevent reverse rotation thereof. 80

In testimony whereof I affix my signature.

EDWARD McKNIGHT. 95
